METHOD FOR DEVELOPING ELECTROSTATIC IMAGES

Lewis E. Walkup, Columbus, Ohio, assignor, by mesne assignments, to The Haloid Company, Rochester, N. Y., a corporation of New York

Application September 18, 1950, Serial No. 185,387

9 Claims. (Cl. 117—17.5)

This invention relates to the development of electrostatic or electrophotographic images and to methods and apparatus for carrying out such development.

The invention has application to the development of electrostatic latent images on electrophotographic plates, such as those described in U. S. Patent No. 2,297,691 to Chester F. Carlson, for example, and other electrostatic images on insulating surfaces. In the process of electrophotography, as described in the Carlson patent, an electrophotographic plate is used comprising a layer of photoconductive insulating material which is usually affixed to a conductive backing plate or film. In the usual method of carrying out the process the plate is first given a uniform electrostatic charge over its surface. The photoconductive layer is then exposed to a light pattern or image in a camera or by contact exposure methods, for example, to bring about a discharge or partial discharge of the electrostatic charge in the areas where light strikes the layer and leave an electrostatic latent image on the layer. If exposure has been made correctly the areas which received the least light retain the highest charge while those which received the most light retain the least charge. Areas which received an intermediate degree of illumination retain an intermediate charge.

The latent image can then be developed by depositing a finely-divided electrostatically attractive material, such as a powder or fine liquid droplets onto the surface of the layer where it is trapped by the electrostatic charges of the image. Where the charge contrast is greatest the greatest amount of material is deposited and where the contrast is least little or no material is deposited. It is thus possible to produce a powder image, for example, substantially conforming to the light image originally projected onto the layer. The powder, or other material, can subsequently be transferred to a sheet of paper or other surface and fixed to produce a permanent print.

Images of line material (drawings, typewriting, printing and the like) and half-tones are reproduced with good fidelity by the electrophotographic process. Continuous-tone images, namely images in which the density varies through several shades of gray as in photographs, radiographs and the like, tend to be reproduced as somewhat contrasty prints by electrophotography. That is, intermediate shades of gray are not all reproduced proportionally. It has also been found that large black or dark areas do not always develop uniformly throughout their whole area but tend to develop more heavily around the edges than in the middle of the areas.

A feature of the present invention resides in methods and apparatus for improving the development of electrostatic images. According to an important aspect of the invention methods and apparatus are utilized to bring about a realignment of the electrostatic field surrounding the electrostatic images during development thereof. A preferred embodiment of the invention resides in the provision of apparatus including a control electrode or elec-

trodes spaced from the image surface and in methods and means for applying control potentials to said electrodes thereby to control the deposition of a developing material, such as a finely-divided electrostatically-attractable material, on the electrostatic image in a predetermined manner.

The invention comprises the features of construction, combination of elements, arrangement of parts, and methods of operation referred to above or which will be brought out and exemplified in the disclosure hereinafter set forth, including the illustrations in the drawing.

In the drawings:

Figure 1 is a top view with parts broken away, of a developing device embodying features of the present invention, said device being arranged for development of an electrostatic image on an electrophotographic plate or other image-bearing surface with a finely-divided powder suspended in air;

Figure 2 is a vertical section on the line 2—2 of Figure 1;

Figures 3 and 4 are enlarged fragmentary views illustrating features of development according to the prior art and according to aspects of the present invention, respectively;

Figures 5, 6, 7 and 8 are graphs illustrating certain characteristics of the exposure and development processes for electrophotographic plates;

Figure 9 is a circuit diagram showing an electric circuit comprising part of the apparatus arranged according to a modification of the invention;

Figure 10 illustrates a modified arrangement suitable for development of an electrostatic image according to a modified technique embodying the use of a sprayed cloud of liquid mist;

Figure 11 is a detail of the liquid spray device; and

Figure 12 illustrates a powder spray device.

While a preferred embodiment of the invention is described herein, it is contemplated that considerable variation may be made in the construction and arrangement of parts and in the method of operation without departing from the spirit of the invention. In the following description and in the claims parts will be identified by specific names for convenience, but they are intended to be as generic in their application to similar parts as the art will permit.

Referring to the drawing, the developing device 20 illustrated in Figs. 1 and 2 comprises a tapered metal chamber or cone 21 with its mouth upward having its narrow end at the bottom provided with a rotating agitator brush 22 driven by electric motor 23. The top flanged end of the cone is clamped beneath a top plate assembly comprising plates 24 and 25 provided with a central rectangular aperture over which a plate 26, such as an electrophotographic plate, carrying an electrostatic latent image, is placed face downward for development. A development control electrode 27 comprising an array of conductors, such as a fine wire grid is mounted in the aperture in spaced relation to the face of plate 26 and connected to a conductor 28 for the application of suitable control potentials to grid 27.

The device is mounted on a flat base or bedplate 29 by four vertical legs 30 which support a rectangular frame 31. The top of cone 21 is provided with a horizontal flange 32 extending outwardly and resting on frame 31. Plate 24, formed of insulating material such as phenol-formaldehyde resin, plate glass, dry wood or other suitably rigid insulating material, is secured on top of flange 32 with its central rectangular aperture 33 disposed directly over the center of the cone. Sheet 25, which is affixed to the top surface of plate 24, is of thin stock, preferably 0.01 inch or less in thickness, and is

also preferably formed of rigid insulating material such as phenol-formaldehyde resin, polystyrene or the like. The central aperture 34 of this sheet is also rectangular in shape but is slightly smaller than aperture 33 so as to provide an overlapping flange around the edge of the aperture 33, as illustrated.

Plate 26, carrying the electrostatic latent image to be developed, may comprise an electrophotographic plate formed of a flat metal plate having a coating 35 of photoconductive insulating material, as described for example 10 in Carlson Patent No. 2,297,691. For purposes of development the plate is placed face down over aperture 34 with coating 35 substantially in the plane of the upper surface of sheet 25.

Development control grid 27 is supported directly underneath the face of coating 35 in spaced parallel relation to it. Grid 27 may comprise a series of fine, parallel wires stretched taut between the two sides of a rigid rectangular metal frame 36. The wire can be strung back and forth over pins 127 on the outside edges of frame 36. Frame 36 is larger than aperture 34 but slightly smaller than aperture 33 so as to fit up under the flange provided by sheet 25 where it overhangs the aperture 33. This enables grid 27 to be brought close to the surface of coating 35 without danger of direct contact. Generally speaking, relatively close spacings are preferred. Frame 36 is provided with a pair of outwardly extending lugs or flanges 37 spaced from the lower face of plate 24 by spacing washers 38 and secured to the plate by screws 39 to provide accurate location of the grid 27. In a preferred embodiment, grid 27 may be formed of 0.0035 inch diameter stainless steel wire and be mounted so as to provide sixty equidistant parallel wires to the inch. While grid to plate spacings between grid 27 and coating 35 of 0.010 inch to 0.5 inch are useful, the most satisfactory range for the grid described is between 0.040 and 0.080 inch.

Cone 21 is preferably formed of metal, such as brass, aluminum, steel or the like. The angle of flare is not critical but for practical operation it is desirable that the conical wall have a sufficiently steep slope to allow developing powder used in the chamber to slide to the bottom either without agitation, or with a slight tapping or vibration of the chamber. The inside surface is preferably smooth or polished to facilitate sliding of the developing powder. The bottom of the chamber is closed by a horizontal, circular disk-shaped wall 40 having a central aperture accommodating the upward extension of rotary shaft 41 upon which brush 22 is mounted within the chamber. By way of example, disk-shaped area 40 may have a diameter of 2" and brush 22 may comprise a pair of oppositely extending one-inch tufts of bristles formed of horsehair or other rather stiff bristles. Shaft 41 is supported vertically for rotation in ball bearing assemblies 42 and 43, and assembly 42 being set into base plate 29 and assembly 43 being supported by a bracket 44 just beneath the bottom of chamber 21. The felt washer 45 surrounding the shaft seals the central aperture in bottom disk 40 against powder leakage. Shaft 41 is provided with a pulley 46 and electric motor 23 mounted with its shaft vertical on frame crosspiece 47 is provided with a pulley 48. A V-belt 49 threaded over pulleys 46 and 48 provides a driving connection between the motor and shaft 41. With an 8" high chamber 21 having a 2" diameter brush 22 at the bottom, a brush speed of 2500 R. P. M. affords suitable agitation for powder placed in chamber 21 in order to develop a cloud of powder within the chamber. A 1725 R. P. M. electric motor may be used with pulley sizes adjusted to provide the desired brush speed.

A potential source such as a battery 50, which may have a potential of several hundred volts is provided for applying a potential difference between grid 27 and back-plate 26 when desired. In order to vary the potential a potentiometer 51 is connected between the terminals of battery 50 and sliding contact 52 of the potentiometer

is connected by conductor 28 to grid frame 36 and, hence, to grid 27. A spring contact 53 mounted on an insulating support post 54 on top of plate 25 is arranged to rest against the back of plate 26 to connect it to ground. A center tap of potentiometer 51 is also grounded. It is thereby possible, by moving sliding contact 52 to adjust the potential of grid 27 to be equal to the potential of plate 26, i. e. at ground potential, or to make grid 27 up to several hundred volts positive or negative with respect to plate 26.

Preparatory to developing an electrostatic latent image with the device illustrated in Figures 1 and 2, a charge of developing powder 55 is placed in conical chamber 21. Suitable powders for this purpose comprise finely-divided black or colored powders either alone or mixed with a granular material having different triboelectric properties in order to generate electrostatic charges on the individual powder particles. By way of example, one suitable developer consists of the following composition.

EXAMPLE

20 cc. of a finely-divided developer powder and 5 cc. of a granular carrier material mixed together. A suitable developer powder may be produced by blending together 25 20 parts of a rosin-modified phenol-formaldehyde resin having a melting point in the order of 142-149° C., such as is sold commercially as Amberol F-71 Resin by The Resinous Products Division of Rohm and Haas Company, Philadelphia, Pennsylvania, and 1 part of carbon black, such as that sold commercially as Raven Bead Carbon Black. The blend is fused and thoroughly mixed, allowed to solidify, crushed and micronized to provide a particle size in which most of the developer particles have a diameter in the range between 1 and 20 microns. The carrier 30 may consist of soybean protein from which the oil has 35 been removed, cut to a size which will pass through a 16-mesh screen and be retained on a 48-mesh screen.

Other developing powders and developing mixtures may 40 also be used in the developing device. Where a carrier-powder mixture is used, the powder and carrier are preferably formed of materials so situated in the triboelectric series that charges are imparted to the powder particles of a polarity opposite to the charge on the electrostatic latent image to be developed. Thus, if the latent image 45 is made up of positive electrostatic charges, it is preferred that the finely-divided developer be formed of a composition which will acquire negative charge by contact with the carrier material. In other words, the developer is formed of a material which is nearer to the negative end 50 of the triboelectric series than the carrier material.

The result of agitating such a powder carrier mixture is to create a powder cloud in chamber 21 which is composed predominately of negatively charged powder particles. The carrier particles, being much larger and heavier, tend to fall back to the bottom of the chamber and 55 do not rise to the developing area at the top.

In operation the developing device may be used to develop an electrostatic latent image on an electrophotographic plate 26 in the following manner. The latent 60 image on coating 35 of the electrophotographic plate may be produced in any known manner. For example, a positively-charged image may be formed by first placing a uniform positive electrostatic charge over the surface of coating 35 by subjecting it to a positive electric discharge from a corona discharge electrode and then exposing the coating by contact exposure with an original to be copied or by exposing the plate in a camera to any subject or scene to be recorded. This exposure discharges the plate 65 in proportion to the light received leaving the electrostatic latent image on the coating. The plate is then placed face down over aperture 34 as illustrated in Figure 2 and ground contact 53 allowed to rest on the back of the plate. Tap 52 is adjusted to the desired potential, as will be described more in detail later, and then, with a charge 55 of 70 developer and carrier mixture in the chamber 21, electric 75 developer and carrier mixture in the chamber 21, electric

motor 23 is started to rotate brush 22 at a speed such as 2500 R. P. M. This produces active agitation of developer mixture 55 and causes a cloud of predominantly negatively charged powder particles to rise in chamber 21, some of the particles rising through grid 27 into the space between the grid and coating 35 where they are attracted to the positively-charged areas of the image and form a powder deposit on coating 35 corresponding to the electrostatic latent image.

With the chamber 8" high, an operation of the agitator brush 22 for between one-half and three minutes is usually sufficient to produce adequate development of the electrostatic latent image. If desired, tap 52 may be moved during development to vary the potential on grid 27 in relation to plate 26 over a range of values which may include potentials both positive and negative with respect to the plate backing as well as equal to the plate potential as will be described more in detail later. If excessive quantities of developer accumulate on the sloping walls of chamber 21, it will be found desirable to tap the chamber occasionally to shake the loose powder down to the bottom. Occasional cleaning of grid 27 may also be required but this needs usually be done only once prior to placing the plate on the apparatus.

After development plate 26 may be removed from the device and the powder image transferred to a sheet of paper or other base by any suitable method such as by pressure contact, or by passing the plate with a sheet of paper laid loosely over the developed coating under a positive corona discharge to attract the negatively-charged powder image to the paper. After transfer the powder image may be fused to the sheet to produce a permanent print. Any loose residual powder on coating 35 may then be removed and the plate used again to form another electrostatic latent image which can be developed in the same manner.

The function of development control grid 27 in controlling the development of the latent image may be more fully explained by reference to Figures 3 to 8. Figure 3 illustrates the effect of developing an electrostatic latent image on an electrophotographic plate with a powder cloud without the use of a development control electrode. The group of plus signs 57 on coating 35 indicate a charged area of the electrostatic latent image corresponding to a dark area of the original image which was used in making the exposure. It would obviously be desirable to develop this area of the coating heavily with powder in order that the resulting picture would have a dark area corresponding to the dark area of the original. However, it will be noted that coating 35 is affixed to conductive base plate 26 and hence the positive charges on the coating induce corresponding negative charges on the coating in plate 26 so that coating 35 acts very much like the dielectric of an electrostatic condenser. The net effect on negatively charged powder particles 56 floating in the air near the surface of coating 35 is the sum of the effects of positive charges 57 on the coating and negative charges 58 induced in backing plate 26. Since coating 35 is very thin and charges 58 are almost equal in amount to charges 57, the net effect on particles 56 is only very slight. Another way of expressing it is to say that very few lines of force coming from the positive charges extend out into the air where the powder particles are floating. Most of the lines of force pass directly through the coating 35 to the backing plate and hence are not available to influence the powder particles to deposit on the coating. Near the edges of the area 57 of positive charges a few lines of force will pass through the air in curved paths which terminate in negative charges in base plate 26 around the margin of the charged area, as shown in Figure 3. These lines of force will capture a few negative powder particles 56 along the edges of area 57 resulting in the development of a rather heavy border around area 57 while leaving a very light, practically undeveloped central area. It will be apparent from this that the tones

of the original being copied will not be very faithfully reproduced in the powder image. Where small dark areas are involved, such as lines, letters, characters and the like, good development is obtained but large dark areas are not developed uniformly and continuous-tone images tend to be contrasty.

Figure 4 illustrates the improvement obtained by adding control grid 27. Grid 27 provides a conductor spaced in front of coating 35 thereby producing a capacitance between charged coating 35 and grid 27. This tends to intensify the number of lines of force extending outward from the charges on coating 35 and reduce the number extending through layer 35 to the conductive backing. The grid also tends to straighten out the lines of force at the edges of charged area as can be seen in Figure 4. The result of this change is to intensify the field in the air near the surface of coating 35 so that negatively charged powder particles 56 floating in this region will be more strongly attracted to all parts of charged area 57. Moreover, due to the straightening out of the lines of force at the edges of the charged area, the tendency to develop a heavy border around the charged area is greatly reduced or substantially eliminated. The result is the uniform development of large dark areas and the increase in latitude of development of continuous-tone images. In other words they are less contrasty.

Grid 27 may be held at the same potential as plate 26 during development in which case the advantages already described are obtained. However, further control of development may be achieved by placing a potential on grid 27 which is different from the potential of backing plate 26.

Figure 5 shows a typical decay curve 59 for an electro-photographic plate. The ordinate of this graph represents the potential of the plate coating on a logarithmic scale after an exposure of a charged plate to the quantity of light indicated along the abscissa. For the curve shown the initial potential of the charge on the coating was in the order of 360 volts. It will be noted that as the quantity of light used for exposure of a given area increased, the potential decreased in substantially a straight line fashion on the semi-log scale to substantially 10 percent of the original potential after which the curve flattens out considerably. In making an exposure of a continuous-tone subject, it is preferred to regulate the exposure so that only the straight line portion of the curve is used, in order to achieve the best fidelity. If such an exposure is made it is evident that the exposure will be stopped before the charge is completely removed from any area of the plate coating. Thus the most brightly illuminated area of the coating, corresponding to the high lights in the subject, may have its potential reduced to the point 60 shown on the curve, while the middle tones will retain a higher potential 61 and the darkest areas of the image will retain nearly all of their original potential as indicated by the point 62.

It is apparent that if the latent image is now developed with powder that the charge remaining on the high lights is capable of attracting some powder, although not as much as the charges on the middle tones and the dark areas. Thus with grid 27 at the same potential as the backing plate, some development of the high lights will be obtained. This may be desirable for some purposes. In other cases, however, it will be desirable to prevent all deposition of powder on the high lights so that they will remain completely white, or nearly so, in the finished print. This can be accomplished by applying a potential to grid 27 substantially equal to the potential on the high-light areas as indicated by horizontal line 63. The preferred potential may most readily be determined by making one or more trial exposures under established conditions and developing the plate with tap 52 experimentally set at a predetermined potential. If the result of the first development indicates that some of the middle tones are not being developed, this means that the posi-

7
tive potential on the grid should be lowered if fuller development of the higher middle tones is desired. If, however, the high lights themselves tend to be too dark, it is an indication that the potential applied to the grid was not high enough to get good high lights. Having once established a grid setting for predetermined plate exposure conditions, it is not thereafter necessary to experiment to obtain the desired results.

The potential control arrangement for grid 27 also permits adjustment of the development for special purposes. For instance, in some cases it may be desired to develop only the dark areas of an image and to eliminate the middle tones as well as the high lights. This can be done by raising the electrode potential to a higher value such as equal to the potential d_1 of the middle tones.

On the other hand, if a heavier powder deposit is desired in all areas, including the high lights, the potential of grid 27 may actually be reversed in polarity and made negative with respect to plate 26 if the electrostatic latent image is positive and the developing powder is negative. This will intensify the powder deposit over all areas of the plate.

While it is preferred to establish the potential of plate 26 by connecting it to ground or to a reference potential, it is not always essential that plate 26 be so connected during development. Thus if the plate 26 is substantially uncharged at the start of operation, the potentials applied to grid 27 will have substantially the same effect on the field between the field and the plate as if the plate were actually grounded or connected to a reference potential.

It is also possible to improve development of a latent image by cycling the potential on the grid during the development as was already indicated. Thus, it is possible to compensate during development for certain failures of the electrostatic image to correspond with the density of the original being reproduced.

Figure 6 is a graph of the potential of the electrostatic latent image resulting from a certain exposure of an electrophotographic plate as a function of the optical density of the original to which it was exposed. The curve 120 is not a straight line, since potential decay is nearly a straight-line function with exposure rather than optical density in the original. (Density varies inversely as the logarithm of the exposure). Figure 6 indicates that a given electrophotographic plate which has been charged to a uniform potential and then given a certain exposure (as determined by intensity of illumination and time of exposure) will have an electrostatic latent image on its surface in which the potential will be P_1 for an area of the plate exposed to a part of the original having density D_1 , and a density P_2 for area exposed to density D_2 and so forth.

Figure 7 shows the substantially straight-line relationship between potential on the electrophotographic plate and the optical density of the developed final print over the potential range of interest for various times of development, T_1 to T_6 , with development control grid 27 set at the high-light potential P_0 (63 in Figure 5). With short development T_1 , the density of all parts of the image is low, but is proportional to the potential difference between the potential on the image and the potential of grid 27. Progressively increased development times T_2 to T_6 produce correspondingly increased densities in each part of the image.

Figure 8 is a graphic representation of a development cycle which will give a density scale in the final print approximating the density scale of the original. The relationship usually preferred for the entire scale of densities appearing in the original can be represented by straight line curve 121 in Figure 8, starting at the origin and passing through the series of points in the graph which represent densities d of the image equal to densities D in the original. Thus, for a point in the original

5 having a density D_1 , the straight line curve 121 indicates a desired density $d_1 = D_1$ for the image.

The curve 120 in Figure 6 can be reasonably well represented by a straight line up to a point corresponding to a density D_1 and potential P_1 . If the value of potential P_1 and the value of $d_1 (= D_1)$ are marked on the appropriate axes of Figure 7 these two values determine a coordinate point on this graph and this point determines the proper development time, such as T_3 , required 10 to achieve this relationship of density and potential. At the same time this one density area is being developed, the other density areas of the plate are also being developed. These areas will generally correspond to optical densities in the original from zero up to some 15 value between one and two, on the conventional scale.

At the end of this first development period, T_3 , the density of the image on the plate can be represented by curve 122 in Figure 8. It will be noted that the lower densities, from zero to d_1 , of the image all come reasonably close to the ideal densities determined by straight line 121. However, the higher densities are insufficiently developed and hence less dense than the higher densities in the original.

It has been found that the higher density areas can be 25 brought closer to the ideal curve 121 by successive periods of development at higher grid potentials. According to a preferred method, a second period of development is added in which the potential on the development grid 27 is raised to potential P_1 corresponding to the density D_1 in the original which is at the top of the acceptably straight portion of curve 120 in Figure 6. When this is done there will be no substantial further development in any areas on the plate which have potentials lower than P_1 . These areas are now completely developed. For the second period of the development cycle, the value D_2 is selected so that curve 120 in Figure 6 and curve 122 in Figure 8 are both reasonably well represented by straight lines between the values D_1 and D_2 . Now, to bring the density of the print up to the desired straight line in Figure 8 for density D_2 , it is necessary to add to the image an increment of density equal to a_1 , Figure 8. If the value of potential P_2 and the value of density a_1 are marked on the appropriate axes of Figure 7 these values determine a coordinate point indicated by the intersection of the dashed lines. This point determines the necessary development time, such as T_4 , on a family of straight line curves t_1 to t_6 originating at P_1 . These curves are the same as curves T_1 to T_6 but are shifted to the right on the potential axis so that they originate at P_1 rather than P_0 . When this second development period is completed, the final density d_2 of the print area corresponding to the original density of D_2 will fall on the desired straight line. The density of the other areas is indicated by curve 122 up to density d_1 and by curve 123 for higher densities.

By further raising the grid potential to equal P_2 and developing for a further period determined by a similar process the higher densities can be further increased as indicated by curve 124. An extension of the process outlined above can make better and better approximations to the straight line desired between original final density. From three to five values of development-grid potential should be sufficient for practical purposes.

The above exposition of the method of arriving at the proper development cycle can be modified in practice; and it is possible to determine an acceptable development cycle from purely empirical tests. In any case, a development cycle needs to be determined only once for a particular combination of plate, total exposure, and development operation. Actual application of the method outlined above indicates that practical values of development time result.

It may not always be desired to have the image equal to the density of the original and it is evident that straight line curves can be drawn in Figure 8 which have greater

or less slope than curve 121 and that development times can be correspondingly adjusted to produce image density ranges approximating these curve slopes.

It is not always necessary that development at the various grid potentials shall take place in the sequence named. The sequence of development steps can be done in any order and it is even possible to cycle the grid potential through the sequence of values several times. The total time of development at each potential may be determined in the manner already indicated in connection with Figures 6 to 8 or by empirical tests. It is also possible to modify the process by varying the grid potential through a continuous series of values by sliding contact 52 up and down on the potentiometer (Figure 2) during development.

Figure 9 is a circuit diagram of a modified potential control circuit for the development grid. According to this arrangement an automatic cycling potentiometer 64 is arranged to vary the potential on grid 27 through a cycle of values during development. Thus the potentiometer may comprise a switch having a rotating contact 65 which moves step by step over five stationary contacts 66 which are connected together in series by four resistances 67, and the end contacts of the series being connected across the terminals of a battery 68. With a 200-volt battery and four equal resistances 67 of each of the contacts 66 will differ from its neighbor by 50 volts. Plate backing 26 of the electrophotographic plate may be connected to intermediate contact 66a so that the potential applied to moving contact 65 will be made both positive and negative with respect to the potential of plate 26 and also, when contact 65 reaches contact 66a, will be equal to the plate potential. The contact 65 may be connected directly to grid 27 but a further measure of control is afforded by connecting contact 65 by conductor 69 to the common terminal of the two 100-volt batteries 70 and 71. The opposite terminals of the batteries are connected across a potentiometer 72 having a sliding tap 73 which is connected to control grid 27. It is thus possible to use tap 73 for manual cycling of the grid potential or to set tap 73 at any desired position to thereby adjust the potential applied by the automatic cycling potentiometer 64. It is obvious that plate backing 26 may be connected directly to one terminal of the battery 68, if desired; also that potentiometer 64 may be divided into as many sections as desired to reduce the voltage jump between sections as much as is wished. Any desired cycling, such as that described in connection with Figure 8, may be achieved by introducing the required voltage source and potentiometer sections.

Moving contact 65 of potentiometer 64 is connected to a rotary shaft 74 which may be driven by an electric motor, such as motor 23, through a speed reducing device. With contact 65 driven at constant speed the time of development at each potential is determined by the relative lengths of stator contacts 66, these contacts being made of lengths proportional to the desired development times at each potential. According to a modification the position of contact 65 is controlled by a program motor which is set to provide any predetermined cycling of the contact 65, and any predetermined length of dwell on each stator contact 66.

Figures 10 and 11 illustrate an arrangement for developing an electrostatic latent image on a coating 35 of electrophotographic plate 26 with a finely-divided liquid spray or mist 131. A liquid 130 is placed in the reservoir 75 of air brush 76 and sprayed by compressed air feed through hose 77 into a space in which plate 26 is suspended face downward over a control grid 78. Grid 78 may be similar to grid 27 described in connection with Figures 1 and 2. As illustrated the grid consists of an open-mesh screen of very fine wires supported between circular frame members 79. A spacer sheet 80 having a rectangular aperture is interposed between the top of the grid support frame and the coating 35 to

afford the desired spacing between the grid and the plate coating.

Air brush 75 may be of conventional construction to provide a liquid feed and an air jet for atomizing the liquid and projecting it as a fine spray or mist. As shown in Figure 11 the working parts of the air brush comprise tubular elements surrounding a central pointed rod 83 providing a central cylindrical liquid passage 81 for feeding the liquid to be sprayed and a surrounding air passage 82 for converging the air around the liquid channel. Pointed rod 83 occupies the central axis of the liquid passage and terminates in a point at the outlet of the air brush. In order to apply a charge to the liquid particles as they are sprayed, a conductive ring electrode 84 is supported around the tip of the air brush so that the jet of liquid droplets is projected out through the ring. Ring 84 is insulated from the air brush but is connected by an insulated conductor 85 to one terminal of a battery 86 or other potential source. The conductive parts of the air brush are connected to the other (grounded) terminal of the battery. This produces an electrostatic field between the liquid outlet of the air brush and ring 84 so that liquid particles leaving the brush acquire electrostatic charges by induction as they are ejected. Development of the electrostatic latent image is effected by blowing the liquid mist atmosphere 131 into the zone underneath the plate to be developed as shown in Figure 10.

In order to apply a charge to the liquid droplets as they emerge, it is preferable that a liquid which is at least slightly conductive be used. The following liquids have been successfully used with the apparatus shown in Figures 10 and 11 to develop continuous-tone electrophotographic images.

Example I

The air brush reservoir was filled with India ink and the spray was directed toward the exposed plate held about two feet in front of the airbrush, while the ring 84 was held at a positive voltage of 1000 volts with respect to the airbrush. Plates were developed in this manner with the plate and grid assembly held in a vertical plane as well as in the horizontal plane shown in Figure 10. Best results were obtained with the plate horizontal and facing downward as shown in Figure 10 so that the surface of the plate is shielded from the direct spray. This allows freely floating droplets to become attracted to the plate without danger of larger droplets having a momentum imparted by the spray gun from being impinged directly against the plate surface. By changing the distance between the plate and airbrush the speed and uniformity of development can be varied. The airbrush was operated from an air pressure source of 30 lbs. per square inch and was adjusted to feed the ink at the maximum rate. Satisfactory development took place in most cases in 20 seconds.

Example II

Water base inks such as fountain pen inks were sprayed in a similar manner and produced successful images. A 1% solution of water-soluble aniline blue, can be used, for example.

Example III

A 10% solution of Oildag, an oil suspension of colloidal graphite produced by Acheson Colloids Corp., Port Huron, Michigan, in carbontetrachloride produced a light image.

Example IV

A 10% solution of printer's ink in carbon tetrachloride produced a fine-grain image which could be transferred to paper by pressure contact.

Example V

A 5% solution of a variety of alcohol-soluble dyes in ethanol produced a dye powder image. Apparently the ethanol evaporated before the spray reached the plate so that the residual dye powder was deposited on the image.

The final print was transferred to paper and intensified by moistening the paper slightly with alcohol.

Example VI

A 20% solution of water-soluble mimeograph ink in water produced a somewhat rough appearing image.

Example VII

A 10% dispersion of lampblack (#10 Lampblack, Monsanto Chemical Company, Camden, N. J.) in methanol deposited a dry fine-grained lampblack image due to the evaporation of the methanol before the spray reached the plate. Good quality prints were produced by transferring the lampblack image to paper electrostatically and also by pressing a layer of sheet material having a pressure-sensitive adhesive (such as rubber cement or moist gelatin) on its surface against the lampblack image.

It is apparent that the liquid spray development method permits a wide variety of inks and pigment materials to be used, permits ready control of the density of the cloud produced and of the charge on the particles and provides images which may be readily transferred to paper or other surfaces.

Figure 12 illustrated a powder spray device including means for imparting a predetermined charge on the powder particles. This comprises a flask 87 supported mouth downward by pedestal 88 from an insulating base 89. A stopper 90 fitted in the mouth of the flask is provided with three tubes. Inlet tube 91 fed through control valve 92 from a source of compressed air terminates just inside the mouth of the flask. A second tube 93 extends to the top of the inverted flask and is also connected through a control valve 94 with the compressed air source. The third tube 95 is an outlet tube and extends from near the top of the inverted flask out through the stopper and is bent at right angles so that the outlet end 96 will direct the issuing stream of air-suspended powder particles through a surrounding metal ring or tube 97 supported in horizontal position from base 89. A fine wire 98 is stretched along the axis of tube 97 supported at one end by tube 95 and the other end by a terminal post 99. A high voltage direct current source is connected between terminal 99 and tube 97 to create a positive corona discharge from wire 98 to the inside walls of tube 97.

In operation a charge of fine powder 100 is placed in the flask and valve 92 is opened to admit compressed air through tube 91 to agitate the powder. Valve 94 is also opened to admit compressed air through tube 93 to help keep the powder in suspension in the flask. Powder-laden air is driven out through outlet tube 95 and through metal tube 97 where it acquires a positive charge from the corona discharge. The issuing charged dust cloud may be used to develop images on plates supported over a control electrode, as shown in Figure 10, for example. Suitable powders include finely-divided lampblack, wood charcoal, anthracite, pigmented resins such as the Amberol-base resin developer powder previously described and many other powdered materials.

While the present invention has general application to the development of electrostatic images on electrophotographic plates, electroprinting plates and the like, it is of especially great value in the development of continuous-tone images and of images containing large dark areas. In such cases the present invention has produced a marked improvement in quality as well as enabled the development of relatively small differences in potential. This has the effect of increasing apparent speed of electrophotographic plates since a developable image can be achieved by a much shorter exposure of the plate. For example, referring to Figure 5, it is possible to give the plate a very short exposure so that the potential on the high lights is reduced only slightly below the initial potential to which the plate was charged. Thus, the high-light potential may be reduced only to the point 61, instead of to point 60, and the middle tones and dark tones

will be proportionally higher. Upon development with a control grid set at a potential equal to point 61 the potential differences in the reduced potential range are readily developed to yield a faithful reproduction of the potential differences in this reduced range.

It is also possible to obtain excellent development of plates initially charged to lower voltages than was possible heretofore. This is because of the effect of the control electrode in increasing the electrostatic field in the air outside the surface of the plate being developed. The lines of force which previously extended through the insulating layer 35 now extend out to the grid 27 so that they can influence powder or liquid particles floating or tumbling between the grid and the electrophotographic plate.

While the present invention, as to its objects and advantages, has been described herein as carried out in specific embodiments thereof, it is not desired to be limited thereby but it is intended to cover the invention broadly within the spirit and scope of the appended claims.

What is claimed is:

1. The method of developing a continuous-tone electrostatic latent image on a surface, wherein said image comprises electrostatic charges of one polarity variously distributed on said surface to provide potentials which differ for different areas of said surface, the low potential areas corresponding to image high lights, the intermediate potential areas corresponding to middle tones and the high potential areas corresponding to shadows and dark tones, which method comprises effecting a plurality of steps of partial development of said image by closely spacing a conductor in front of said surface and introducing an air suspension of a finely-divided material between said conductor and said surface, at least one of said steps being performed with said conductor held at high-light potential and other of said steps being performed with said conductor held at intermediate potentials, said finely-divided material being charged to a polarity opposite to that of said image.

2. A xerographic method of developing an electrostatic image corresponding to a photographic reproduction of a pattern of light and shadow to be recorded, said image being borne by a thin, uniform, photo-conductive insulating layer directly overlying a conductive surface, the developing method comprising positioning a conductive electrode substantially coextensive with said image surface and closely spaced from said image surface at a distance close enough to the electrostatic image so that the electrostatic lines of force that emanate outwardly from the different potential areas on the electrostatic image surface tend to flow mostly to the electrode rather than to other potential areas, and projecting into the space between the electrode and the image surface a gas suspension of charged, finely-divided developer particles whereby said developer particles are deposited in improved conformity with the electrostatic image.

3. A xerographic method of developing an electrostatic image corresponding to a photographic reproduction of a pattern of light and shadow to be recorded, said image being borne by a thin, uniform, photoconductive insulating layer directly overlying a conductive surface, the developing method comprising positioning a conductive electrode substantially coextensive with said image surface and closely spaced from said image surface at a distance close enough to the electrostatic image so that the electrostatic lines of force that emanate outwardly from the different potential areas on the electrostatic image surface tend to flow mostly to the electrode rather than to other potential areas, and projecting into the space between the electrode and the image surface a gas suspension of charged, finely-divided liquid droplets of developer, whereby said developer is deposited in improved conformity with the electrostatic image.

4. A xerographic method of developing an electrostatic

image corresponding to a photographic reproduction of a pattern of light and shadow to be recorded, said image being borne by a thin, uniform, photo-conductive insulating layer, the developing method comprising positioning an insulating layer over said photoconductive insulating layer and in contact therewith and placing a conductive electrode substantially coextensive with said image surface and closely spaced from said insulating layer at a distance close enough to the electrostatic image so that the electrostatic lines of force that emanate outwardly from the different potential areas on the electrostatic image surface tend to flow mostly to the electrode through the said insulating layer rather than to other potential areas, and projecting into the space between the electrode and the insulating layer a gas suspension of charged, finely-divided developer particles, whereby said developer particles are deposited in improved conformity with the electrostatic image.

5. A xerographic method of developing an electrostatic image corresponding to a photographic reproduction of a pattern of light and shadow to be recorded, said image being borne by a thin, uniform, photo-conductive insulating layer, the developing method comprising positioning an insulating layer over said photoconductive insulating layer and in contact therewith and placing a conductive electrode substantially coextensive with said image surface and at a distance close enough to the electrostatic image so that the electrostatic lines of force that emanate outwardly from the different potential areas on the electrostatic image surface tend to flow mostly to the electrode through the said insulating layer rather than to other potential areas, and projecting into the space between the electrode and the insulating layer a gas suspension of charged finely-divided liquid droplets of developer, whereby said developer is deposited in improved conformity with the electrostatic image.

6. The method of developing a continuous tone electrostatic image on a uniform photoconductive insulating surface wherein said image comprises electrostatic charges of one polarity variously distributed on said surface to provide potentials which differ for different areas of said surface, the low potential areas corresponding to image highlights, the intermediate potential areas corresponding to middle tones, and the high potential areas corresponding to shadows and dark tones, which method comprises closely spacing a conductor substantially coextensive with said image at a distance close enough to the electrostatic image so that the electrostatic lines of force that emanate outwardly from the different potential areas on the electrostatic image surface tend to flow mostly to the electrode rather than to other potential areas and introducing an air suspension of a finely-divided material between said conductor and said surface while maintaining said conductor at a potential corresponding to the highest potential on the said surface and of the same polarity as the potential on the said surface, said potential corresponding to the potential of that part of the surface representing the darkest tone of the image to be reproduced, said finely-divided material being charged to a polarity to that of the original image.

7. The method of developing a continuous tone electrostatic image on a uniform photoconductive insulating surface wherein said image comprises electrostatic charges of one polarity variously distributed on said surface to provide potentials which differ for different areas of said surface, the low potential areas corresponding to image highlights, the intermediate potential areas corresponding to middle tones, and the high potential areas correspond-

ing to shadows and dark tones, which method comprises closely spacing a conductor substantially coextensive with said image at a distance close enough to the electrostatic image so that the electrostatic lines of force that emanate outwardly from the different potential areas on the electrostatic image surface tend to flow mostly to the electrode rather than to other potential areas and introducing an air suspension of a finely-divided material between said conductor and said surface while maintaining said conductor at a potential corresponding to the lowest potential on the said surface and of the same polarity as the potential on the said surface, said potential corresponding to the potential of that part of the surface representing the lightest tone of the image to be reproduced, said finely-divided material being charged to a polarity opposite to that of said image.

8. A xerographic method of developing an electrostatic image corresponding to a photographic reproduction of a pattern of light and shadow to be recorded, said image being borne by a thin, uniform, photoconductive insulating layer directly overlying a conductive surface, the developing method comprising positioning a conductive electrode in the form of a grid substantially coextensive with said image surface and closely spaced from said image surface at a distance close enough to the electrostatic image so that the electrostatic lines of force that emanate outwardly from the different potential areas on the electrostatic image surface tend to flow mostly to the electrode rather than to other potential areas, and projecting into the space between the electrode and the image surface a gas suspension of charged, finely-divided developer particles whereby said developer particles are deposited in improved conformity with the electrostatic image.

9. The method of making a visible pattern on a surface which comprises forming an electrical charge-pattern on said surface in which different areas have different potentials, positioning an electrically-conductive foraminous grid structure so that it is separated from but disposed close enough to said surface so that the electrical lines of force that emanate outwardly from the different potential areas on said surface tend to flow mostly to the grid structure rather than to other potential areas on said surface, and directly previously electrically-charged marking particles through said grid structure into the electrical field of said pattern.
